UNITED STATES PATENT OFFICE.

JACOB SOKOLOV, OF BROOKLYN, NEW YORK, ASSIGNOR OF ONE-HALF TO JOHN FIRTH,
OF NEW YORK, N. Y.

WRENCH.

1,108,264.

Specification of Letters Patent. Patented Aug. 25, 1914.

Application filed July 1, 1913. Serial No. 776,748.

To all whom it may concern:

Be it known that I, JACOB SOKOLOV, a citizen of the United States, residing at Brooklyn, State of New York, have invented certain new and useful Improvements in Wrenches, of which the following is a specification.

It is the object of my invention to provide a simple and effective construction of 10 ratchet wrench permitting the wrench head to rotate in either direction by the handle by ratchet action or to be locked in fixed relation with respect to the handle. To these ends I have provided a construction of 15 the character hereinafter described and claimed.

For an illustration of one of the forms my invention may take reference is to be had to the accompanying drawing, in which:

20 Figure 1 is a plan view of a wrench embodying my invention. Fig. 2 is a vertical sectional view, on enlarged scale, taken on the line A—A of Fig. 1. Fig. 3 is a perspective view of the locking means. Fig. 4 25 shows in plan view the wrench head with locking means, the handle and screw dismembered from each other.

The wrench head H has formed thereon the one jaw member J, the other jaw member J' having formed thereon the member A movable longitudinally in a channel or groove in the head member H. The member A has at its one edge the teeth T with which meshes the worm W supported in and 30 rotatable with respect to the head member H, rotation of the worm W causing movement of jaw J' with respect to jaw J to accommodate different sized nuts or bolts to be actuated by the wrench.

40 In the head H, with its axis at right angles or normal to the plane of movement of the head H is the cylindrical socket S having at its bottom the inturned flange or lip F. Movable vertically in the socket S, and rotatable therein, is the cylindrical member B within which is housed the spring C which rests at its lower end upon the flange F and thrusts upwardly upon the end of the cavity within the member B. Upon the member B is the horizontally 45 disposed circular member D having a plurality of depressions or other roughening means E for creating friction between the member D and a thumb or finger for easily 50 rotating the locking means. Upon the up-

per face of the disk or ring D is the detent member G having the substantially parallel faces K and L, the upper sloping or inclined face M and the substantially vertical face N.

60 The wrench handle O has at its one end a circular aperture P through which extends the shouldered screw Q which engages in the head H by screw threads R, one side of the shank of the screw Q being 65 flattened as at U, to allow free rotation of the milled disk D. Around the aperture P in the handle O are the slots V of a width slightly greater than the width of the detent member G.

70 In assembling the wrench, the shell B and spring C are introduced into the socket S, then the handle member O is placed in position on top of the detent member G, forcing the same downwardly, as viewed in 75 Fig. 2, and then the nut Q is introduced and screwed home. In so assembling the parts, the member B may be depressed out of the way of the nut Q, which, when screwed home, preferably has the notch or 80 shoulder U on the side next to the projection D used in actuating the member G.

85 The operation is as follows: The operator may rotate the detent member G by applying his finger or thumb to the milled disk D. He may rotate the disk D so as to bring the detent member G into alignment with any of the slots V in the handle O in which case the spring C will raise the detent member G into the slot V, the faces 90 K and L of the detent member G in such case lying parallel to the side faces of the slot V. In such case the head H of the wrench is locked in fixed position with respect to the handle O, and force may be 95 applied in either direction to the head H so that the wrench operates as if the head H were fixed to the handle O.

100 To transform the wrench into a ratchet wrench, the operator rotates the disk D, after depressing the same in opposition to spring C to withdraw detent member G from the slot V; and he may rotate it to a position substantially at right angles to the position above described in which case 105 the top edge or portion X of the detent member G will extend into a slot V, being held therein by the spring C and will engage against one side of the slot V, in which case movement of the handle toward 110

the detent G will cause a thrust of the handle against the same and therefore apply a rotating force to the head H. When the handle has been partially rotated, it is rotated in opposite direction in which case the inclined surface M of the detent engages the opposite edges of the successive slots, and rides over them and in so doing depresses the detent member in opposition 10 to spring C and as the detent member comes into alignment with the successive slots it snaps up into the same so that the handle can be again rotated in the first named direction to give a further rotative movement 15 to the head H. And by rotating the detent member G through one-half a revolution from the last named position the head H may be rotated by ratchet action in opposite direction to that last described.

20 What I claim is:

1. In a wrench, the combination with a head, of a detent member carried thereby and movable normally at right angles to the plane of movement of said head, a 25 handle pivotally mounted upon said head, said handle having a plurality of grooves or slots adapted to receive said detent, and means for depressing and rotating said detent, said detent member adapted to engage in said grooves or slots in three positions, whereby said handle may drive said head in either or both directions.

2. In a wrench, the combination with a wrench head, of a cylindrical socket therein, 35 a hollow cylindrical shell adapted to move longitudinally in said socket at right angles to the plane of movement of the wrench head and to rotate in said socket, a handle pivoted to said head, said handle having a 40 plurality of grooves or slots, and a member carried by said shell and adapted to engage in said grooves or slots.

3. In a wrench such as described, a handle member, a rotatable head carried by said 45 handle member, said handle member having radial notches formed therein, a detent

member carried by the head and movable to engage said notches, said detent member having a projection thereon provided with two parallel faces adapted when the detent 50 is in one position to engage the sides of the notches and when said detent member is in the position opposite thereto to extend at right angles to the said notches, said projection having a second pair of 55 faces extending at right angles to the parallel faces, said second mentioned faces being disposed in angular planes, said second mentioned faces terminating short of the first mentioned faces producing shoulders 60 adapted to engage the wrench handle upon opposite sides of the notches when the projection is disposed at right angles to the notches, means for forcing said detent member in the direction of the notches of the 65 handle, and means whereby said detent member can be operated.

4. In a wrench such as described, a handle member, said handle member having radial notches formed therein, a head having a socket formed therein, a detent member rotatable and slidable in said socket, said detent member comprising a cylindrical body portion having a milled periphery projecting through said head member, a 70 sleeve extending from one side of said body portion of the detent member and a boss, having angularly disposed end surfaces, projecting from said body portion, upon the side opposite to the sleeve, for engagement with the notches in the handle member, and a spring interposed between the detent member and body portion and disposed within the sleeve.

In testimony whereof I have hereunto 75 affixed my signature in the presence of the two subscribing witnesses.

JACOB SOKOLOV.
